UNITED STATES PATENT OFFICE.

THOMAS H. RAE, OF FARMINGTON, CALIFORNIA.

AXLE-SET.

1,073,571.

Specification of Letters Patent. Patented Sept. 16, 1913.

Application filed August 26, 1912. Serial No. 717,061.

To all whom it may concern:

Be it known that I, THOMAS H. RAE, a citizen of the United States, residing at Farmington, in the county of San Joaquin,

5. State of California, have invented certain new and useful Improvements in Axle-Sets; and I do declare the following to be a clear, full, and exact description of the same, such as will enable others skilled in the art to 10 which it appertains to make and use the same, reference being had to the accompanying drawings, and to the characters of reference marked thereon, which form a part of this application.

15. This invention relates to improvements in means for setting axles at the proper angle as is necessary to the perfect operation of the wheels upon such axles, the object of the invention being to produce a tool by 20 means of which the exact degree at which the axle is to be set can be determined without the need of computing the same from measurements and figures.

A further object of the invention is to 25 produce a simple and inexpensive device and yet one which will be exceedingly effective for the purposes for which it is designed.

These objects, I accomplish by means of 30 such structure and relative arrangement of the parts as will fully appear by a perusal of the following specification and claims.

On the drawings similar characters of reference indicate corresponding parts in 35 the several views.

Figure 1 is a top plan view of the complete device. Fig. 2 is a fragmentary view of the same showing it in use. Fig. 3 is a sectional view of a portion of an adjustment 40 frame. Fig. 4 is a top plan view of an extension member. Fig. 5 is a side elevation of an adjustment pin. Fig. 6 is a sectional view of an indicator. Fig. 7 is a side elevation of a guide.

45. Referring now more particularly to the characters of reference on the drawings, the numeral 1 designates a straight member provided with an elongated slot 2 in one end and with a recess 3 in its top face to receive the head of a bolt hereinafter described, disposed over one side of which recess is a plate 4.

The numeral 5 designates an adjustment bar or guide frame pivotally mounted on 50 the member 1 as at 6 and provided with a guide slot 7 in its lower end, which slot 7 is

disposed just above the recess 3. The member 5 is also provided on its end with a transverse slotted guide 8 secured thereto through which projects a bolt 9 carrying a wing nut 10, which bolt 9 is secured in the member 1, whereby by the operation of the wing nut 10, the guide 8 and incidentally the member 5 will be fixed stationary with respect to the member 1. The member 5 is 55 provided with an adjustable extension 5^a at one end having a fork 5^b which fits over the end of the member 5 and is adjustable thereon, any desired fixed position of the member 5^a—5^b with respect to the member 5 70 being determined by a wing nut 5^c which is mounted on the bolt 6 and is adapted to impinge against the members 5 and 5^a.

Mounted on the member 5 is a transverse slotted indicator 11 which is adjustable longitudinally along said member 5 and which may be secured in place by means of a bolt 12 and wing nut 13, which bolt 12 projects through the slot 7 and its head bearing against the member 5 on each side of the 80 slot 7 and projecting into the recess 3 and then when the wing nut 13 is screwed down it clamps the member 11 stationary with respect to said member 5. Said member 11 is also similarly adjustable transversely 85 across the member 5 by means of its slot 14 through which the bolt 12 projects.

The numeral 15 designates bars provided with curved yokes 16, which members 15 are secured to each end of the member 1, 90 one of said members 15 being adjustable along the length of said member 1 by means of a bolt 17 which projects through the slot 2 and a wing nut 18 mounted thereon, there being a projecting flange 19 on the member 95 15 to keep it from turning with respect to the member 1.

Screwed into one end of the member 5^a is a pin 20 having a threaded portion 21 provided with sixteen threads to the inch. 100 Said pin 20 is provided with finger operating member 22 whereby it may be turned on its threads.

The numeral 23 designates a nut which abuts against the member 5^a to determine 105 the normal position of the pin 20, which normal position is such that the length of said pin projecting beyond the member 5^a is equal to the length of the member 15.

The operation of the device is as follows: 110 When it is desired to set the axle, the lower end of the member 5 is set at a definite po-

sition with relation to the member 1. The member 1 is disposed against the outsides of the fellies 24 of the wheel for which the axle is to be set and then the indicator 11 is projected across to engage the side of the lower end of one of the spokes 25 which action causes the position of the indicator 11 to indicate the depth of the dish of the wheel. The indicator 11 is then set 10 in fixed position by means of the wing nut 13 and then the member 5 is moved on its pivotal point 6 by means of the slotted guide 8 until a projecting flange 11^a on the indicator bears against the plate 15 4 which thus moves the member 5 at its outer end a proportionate distance. This position of the member 5 is then fixed by the operation of the wing nut 10. The entire device is then mounted on the axle 26 just 20 outside the collars 27 by means of the members 15, the yoke 16 fitting over the axle 26 just outside the collar 27 as shown in Fig. 1 and on top of the axle. The member 20 is then at such a position that its end designates the point at which the spindle 28 of 25 the axle must be bent to provide for the dish of the wheel for such spindle provided such spindle was not tapered, but inasmuch as the spindle is tapered, a further adjustment is necessary and thus this is accomplished by 30 turning the pin 20 on its threaded portion 21, one or more turns as indicated by the finger members 22 until such pin 20 has been moved a sufficient distance to compensate for the taper of the member 28. For instance, if the member 28 had a taper of 35 an eighth of an inch and the pin 20 had sixteen threads to the inch, then the member 20 would be turned one turn which would move it one-sixteenth of an inch which is necessary 40 to compensate for one-half of the one-eighth taper of the member 28 and then when the spindle 28 is bent to touch the end of the member 20, it will then be set at the proper 45 angle to compensate for the dish of the wheel and for its taper which will fully appear in the foregoing description. One of the members 15 which is adjustable as described is movable as may be found desirable for different lengths of the axles.

The above operation describes the method of setting the spindle for compensating for the dish of the wheel and the device can also be used for setting the axle for the 55 gather of the wheel by the following operation, namely: The member 5 is set parallel with respect to the member 1 and the member 20 is screwed up until the nut 23 abuts against the member 5^a. The yokes 16 are 60 then fitted against the side of the spindle 28 and the spindle 28 then is bent to touch

the end of the member 20 which then gives the set necessary to compensate for the gather of the wheels.

From the foregoing description it will be 65 readily seen that I have produced such a device as substantially fulfills the objects of the invention as set forth herein.

While this specification sets forth in detail the present and preferred construction of 70 the device, still in practice such deviations from such device may be resorted to as do not form a departure from the spirit of the invention.

Having thus described my invention what 75 I claim as new and useful and desire to secure by Letters Patent is:

1. A device of the character described comprising a straight member, a guide frame pivotally mounted on said straight 80 member and normally projecting longitudinally therewith, an indicator disposed transversely on said guide frame and being adjustable thereon, means for fixing said guide frame stationary with respect to said 85 straight member, and means for fixing said indicator stationary with respect to said guide frame, as described.

2. A device of the character described comprising a straight member, a guide 90 frame pivotally mounted on said straight member and projecting normally longitudinally therewith, means for fixing said guide frame stationary with respect to said straight member and an indicator adjustable longitudinally and transversely on said 95 guide frame, as described.

3. A device of the character described comprising a straight member, a guide frame pivotally mounted on said straight 100 member, an adjustable extension on said guide frame, an indicator adjustably mounted on said guide frame, means for fixing said guide frame stationary with respect to said straight member, and a pin disposed 105 at right angles to the outer end of said extension, as described.

4. A device of the character described comprising a straight member, a guide frame pivotally mounted on said straight 110 member, means for fixing said guide frame stationary with respect to said straight member, an indicator adjustable on said guide frame, said indicator being provided with a flange adapted to engage the side of 115 said straight member, as described.

In testimony whereof I affix my signature in presence of two witnesses.

THOMAS H. RAE.
